ATTORNEY

UNITED STATES PATENT OFFICE.

HARRY B. STEARNS, OF OAKLAND, CALIFORNIA.

DESIGN FOR A BUILT-IN COMBINED CHINA-CLOSET AND WRITING-DESK.

46,351.

Specification for Design.

Patented Sept. 1, 1914.

Application filed June 29, 1914. Serial No. 848,095. Term of patent 3½ years.

To all whom it may concern:

Be it known that I, HARRY B. STEARNS, a citizen of the United States, residing at Oakland, in the county of Alameda and State of California, have invented a new, original, and ornamental Design for a Built-In Combined China-Closet and Writing-Desk, of which the following is a specification, reference being had to the accompanying drawings, forming part thereof.

I claim:

The ornamental design for a built-in combined china closet and writing desk, as shown.

HARRY B. STEARNS.

Witnesses:

IRVINE SINNETT,
HARRY P. THOMAS.
